UNITED STATES PATENT OFFICE.

PHILIP OTT, OF NEW YORK, N. Y.

DESIGN FOR A HATCHET.

SPECIFICATION forming part of Design No. 29,146, dated August 2, 1898.

Application filed April 1, 1898. Serial No. 676,143. Term of patent 14 years.

To all whom it may concern:

Be it known that I, PHILIP OTT, a citizen of the United States, residing in the borough of Manhattan, in the city and county of New York and State of New York, have invented and produced a new and original Design for Hatchets, of which the following is a specification, reference being had to the drawings forming a part thereof.

Figure 1 is a side elevation of a hatchet showing my design, and Fig. 2 is an edge view thereof.

The leading feature of my design consists in a hatchet having an outwardly-opening slot in the cutting edge of the hatchet and a caved depression at the inner edge, and in which is shown an outwardly-opening slot and above which is another outwardly-opening slot.

Referring to the drawings, 1 designates the cutting edge of the hatchet, in which is the outwardly-opening slot 2, and 3 is the inner edge, in which is formed a concavity or depression 4, within which is located an outwardly-opening slot 5, and above this slot 5 is another outwardly-opening slot 6. Above the slot 6 is the opening 7 for a handle, and above this opening is the angular hammer-head 8.

What I claim is—

The design for a hatchet substantially as shown and described.

PHILIP OTT.
